UNITED STATES PATENT OFFICE.

WILLIAM E. WALSH, OF LOWELL, MASSACHUSETTS.

MEANS FOR REMOVING FLUFF OR DUST FROM SPINNING-FRAME GUIDES.

1,309,790.

Specification of Letters Patent. Patented July 15, 1919.

Application filed November 18, 1918. Serial No. 262,960.

To all whom it may concern:

Be it known that I, WILLIAM E. WALSH, a citizen of the United States, residing at Lowell, in the county of Middlesex and State of Massachusetts, have invented an Improvement in Means for Removing Fluff or Dust from Spinning-Frame Guides, of which the following description, in connection with the accompanying drawings, is a specification, like characters on the drawings representing like parts.

The invention to be hereinafter described relates to spinning machines.

In these machines it is customary to provide guides between the drawing rolls and the spindles to guide the rovings passing from the drawing rolls to the spindles. These rovings being of light, delicate character, deposit fluff or dust on the guides which accumulates and is liable to catch on the rovings and form enlargements thereon, which either will not pass through the guides and therefore cause the rovings to be broken, or will produce lumps on the yarn, impairing its quality.

A continuous current of air directed to the guides will clear the fluff or dust therefrom, but a continuous current is liable to break the light, delicate rovings, and if broken from this or other causes, the continuous current of air will blow the loose ends of the rovings about, thereby rendering it difficult to pick up and reconnect the ends of the rovings, and frequently the loose ends are blown over to and unite with rovings passing to adjacent spindles.

The present invention utilizes an air current for removing the fluff and dust from the guides, but the current is applied intermittently in the form of gentle puffs of air with a frequency sufficient to prevent objectionable accumulation of fluff or dust on the guides, but with intervals of substantial duration between the puffs when there is no air current on the rovings, and therefore, no liability of breaking the same, and if the rovings should be broken from other cause, the intervals afford the operator sufficient opportunity to pick up and reconnect the loose ends of the rovings.

The character of the invention will be best understood from the following description of one good form of means for carrying the invention into practical effect, shown in the accompanying drawing, wherein:

Figure 1 is a conventional showing of an

assembly of members typifying parts of a spinning machine and equipped with one form of means which may be employed to produce the intermittent puffs of air on the guides; and

Fig. 2 is a plan of the parts shown in Fig. 1.

Referring to the drawing, 1 designates a spindle typifying one of the spindles of a spinning machine which may be operated by means well known in the art, and therefore, unnecessary to illustrate herein. 2 and 3 typify the usual drawing rolls of a spinning machine mounted on shafts 5 and 7 driven in the usual manner. The rovings 9 pass between the drawing rolls to the spindles 1, and are guided in their passage therebetween by guides, in the present instance, in the form of slots 11 (Fig. 2) in a board 13 connected by hinges 15 with an inclined plate 17 mounted on and secured to the frame member 19.

The character of the rovings is such that as they pass through the guide slots 11, they deposit fluff or dust on the board 13 adjacent said slots as indicated at 21. This dust if allowed to accumulate will eventually catch onto the rovings and form enlargements which, as stated, will either check the passage of the rovings through the slots and cause the same to be broken, or if the enlargements are pulled through the slots without breaking the rovings, they will produce lumps in the yarn which will impair its quality.

Next will be described one good form of means for producing the intermittent puffs of air on the guides to remove the fluff or dust therefrom. This means, in the present instance, comprises a bellows 23 having a plate 25 secured to the frame member 19 and a movable or hinged plate 27. This bellows may be of a length sufficient to produce the intermittent puffs of air on the guides for a series of spindles of any number as desired, and the bellows may be provided with an air discharge mouth 29 desirably in the form of a slit extending along and adjacent to the upper surface of the frame member 19.

Any suitable means may be provided for operating the bellows. In the present instance, this means comprises an arm 31 secured to the hinged plate 27 adjacent the free edge thereof and adapted to be engaged at intervals by a roller 33 on an arm 35 fast on a shaft 37 journaled in bearings in the

frame. This shaft may be provided with any appropriate driving means to continuously rotate the same. In the present instance, the shaft has a pulley 39 fast thereon 5 connected by a belt 41 with a similar pulley 43 on a countershaft.

In operation, the roller 33 once in each rotation of the shaft 37 will engage the arm 31 and thereby rock the hinged plate 27 of 10 the bellows upward to expand the latter and fill the same with air. After the roller has lifted the bellows arm as described, it will pass beyond said arm and thereupon the bellows will be gradually collapsed by the 15 weight of the hinged plate 27. This will produce a gentle puff of air in the form of a stream passing from the mouth of the bellows and directed thence along the top of the guide member 19 and the inclined 20 plate 17 to the board 13. In passing over the latter, it will blow the fluff or dust on the guide board adjacent the slots 11 and remove the same therefrom. While the bellows is collapsing, the roller 33 will slowly 25 continue on around and eventually will again lift the arm 31 and expand the bellows. The shaft for the bellows actuating device may be rotated at varying speeds according to conditions as desired, the speed being so 30 regulated that it will produce the puffs with sufficient frequency to prevent objectionable accumulation of fluff or dust on the guides. Since the fluff or dust is not allowed to accumulate in substantial amount on the 35 guides, merely a gentle current of air will suffice to remove the same therefrom, and the force of the current will not be sufficient to break rovings of normal character. If, however, the rovings should be locally at- 40 tenuated or weakened to such an extent that the air current will break the same, or if the rovings become broken from other cause, the intervals between the puffs of air are sufficient to enable the operative to readily 45 pick up and connect the ends of the rovings. The broken ends of the rovings will not be blown about and render it difficult for the operator to pick up the same, and there will be no danger of blowing the loose ends 50 of the rovings over to unite with adjacent rovings.

By the invention simple and effective means is provided for removing the fluff or dust from the guides, and while this means, 55 in the present instance, is in the form of a bellows, it will be understood that other means may be employed for producing the intermittent puffs of air as described.

Having described one good form of the

invention without limiting the same thereto, 60 what I claim as new and desire to secure by Letters Patent is:—

1. In a spinning machine, the combination of drawing rolls, a spindle, a guide for a roving between said rolls and spindle, and 65 means to produce intermittent puffs of air to remove fluff or dust from said guide.

2. In a spinning machine, the combination of drawing rolls, a spindle, means to guide a roving in its transit from the rolls to the 70 spindle, a bellows to produce intermittent puffs of air to remove fluff or dust from said guide, and means automatically to operate said bellows.

3. In a spinning machine, the combination 75 of drawing rolls, a spindle, a guide for a roving between the drawing rolls and spindle, means to produce intermittent puffs of air, and means to direct the air to said guide to prevent accumulation of fluff or dust 80 thereon such as might break the roving or impair the spun yarn.

4. In a spinning machine, the combination of drawing rolls, a spindle, a guide for a roving between said rolls and spindle, and 85 means to produce intermittent puffs of air on the guide to remove fluff or dust therefrom and comprising a bellows, a rotary member, and means actuated by said rotary member for operating said bellows. 90

5. In a spinning machine, the combination of a series of drawing rolls, a series of spindles, a series of guides for rovings between said rolls and spindles, and a bellows common to said guides for producing occasional 95 puffs of air to remove fluff or dust from said guides.

6. In a machine of the character described, the combination of a guide for a roving, air receiving means having a mouth directed 100 toward said guide, and means for automatically causing intermittent puffs of air to pass from said mouth to said guide to remove fluff or dust therefrom.

7. In a machine of the character described, 105 the combination of a member having guide openings for rovings therein, air receiving means having a discharge mouth of sufficient length to deliver a current of air to said guide openings, and means for causing 110 the air to pass from said mouth in the form of intermittent puffs to remove fluff or dust from portions of said member adjacent said guide openings.

In testimony whereof I have signed my 115 name to this specification.

WILLIAM E. WALSH.
